UNITED STATES PATENT OFFICE

2,101,041

LASTING MACHINE

Benjamin E. Blanchard, Swampscott, Mass., assignor to United Shoe Machinery Corporation, Paterson, N. J., a corporation of New Jersey

Application December 8, 1936, Serial No. 114,840

32 Claims. (Cl. 12—2)

This invention relates to lasting machines having means for shaping an upper over a last and for driving fastenings to fasten the upper to a sole or insole (hereinafter frequently referred to as the sole). It is an object of the invention, among others, to provide a machine for lasting a shoe or a portion thereof either with driven fastenings or without driven fastenings, as when cement is used to secure the upper in lasted relation to the sole. The invention is herein illustrated as applied to a machine of the type disclosed in United States Letters Patent No. 584,744, granted on June 15, 1897, upon an application of S. W. Ladd and R. F. McFeely, although it is to be understood that in various novel aspects the invention is not limited to machines of that particular character.

Machines of the type disclosed in the above-mentioned Letters Patent include in their organization a gripper for pulling an upper over a last successively in different locations as the shoe is presented in different positions by the operator, a wiper movable inwardly over the bottom of the shoe in each lasting location to wipe the marginal portion of the upper over the outer face of the sole, and a driver for driving a tack from the wiper to fasten the upper to the sole. In such machines the wiper is provided with a pocket into which a tack is fed, by separating mechanism, in each cycle of the machine from one or the other of a pair of raceways which are adapted to supply tacks of different lengths and which may be shifted to bring one or the other of them into operative relation to the separating mechanism and the wiper. The present invention provides novel means for operating the wiper by a hammer blow to cause the wiper to force the overwiped margin of the upper firmly into adhering relation to the sole in lasting the shoe with cement instead of with tacks. As herein shown, this means comprises a spring-operated hammer which is inoperative when tacks are used but which may be rendered operative at will to deliver a blow to the wiper substantially at the end of its movement inwardly over the shoe bottom. In order that no tacks will be inserted when the hammer is in use, there is further provided novel means for preventing operative movement of the driver, and also novel means for moving the raceways out of operative relation to the separating mechanism and the wiper to interrupt the feeding of the tacks. In the illustrated construction, the wiper is mounted for swinging movement heightwise of the shoe to render it more effective to press the upper into

adhering relation to the sole in lasting with cement. In order to prevent accidental displacement of the wiper during the tack-feeding and driving operations there is further provided novel means for normally preventing swinging movement of the wiper heightwise of the shoe but for releasing it to permit such swinging movement substantially at the end of its overwiping movement when the above-mentioned hammer is in operation. Preferably and as illustrated, the arrangement is such that by the use of a single-controlling member the operator may render the fastening-inserting means operative and the hammer inoperative, or the hammer operative and the fastening-inserting means inoperative, to cause the machine to drive tacks or to force the overwiped margin of the upper by impact against the outer face of the sole in lasting the shoe with cement instead of with tacks.

The above and other features of the invention, including novel means for adjusting the position of an edge gage to vary the position of the shoe laterally when the hammer is in use and various novel details of construction and combinations of parts, will now be more particularly described by reference to the accompanying drawings and pointed out in the claims.

In the drawings,

Fig. 1 is a view in side elevation looking from the right of the head of a machine in which the invention is embodied, showing the parts in the positions that they occupy when the machine is set for lasting a shoe with tacks;

Fig. 2 is a view in side elevation looking from the left of a portion of the structure shown in Fig. 1;

Fig. 3 is a view partly in front elevation and partly in section of a portion of the mechanism shown in Fig. 2;

Fig. 4 is a plan view of a portion of the structure shown in Fig. 3;

Fig. 5 is a view similar to Fig. 4 but showing the parts in the positions that they occupy in lasting with cement instead of with tacks;

Fig. 6 is a view in side elevation of a portion of the head of the machine with the parts in the positions shown in Fig. 4;

Fig. 7 is a view similar to Fig. 6 showing the positions of the parts at the end of the overwiping operation in lasting with cement;

Fig. 8 is a detail view showing the relative positions of the wiper and the shoe positioning means at the end of the overwiping operation and just prior to the tack driving operation;

Fig. 12 is a detail view partly in front elevation and partly in section of a portion of the mechanism shown in Fig. 3;

Fig. 13 is a sectional view illustrating the mounting of the wiper;

Fig. 14 is a detail view of parts shown in Fig. 4;

Fig. 15 is a bottom plan view of a portion of the means for adjusting the edge gage;

Fig. 16 is an end view of the parts shown in Fig. 15;

Fig. 17 is a plan view of the wiper; and

Fig. 18 is a perspective view of a shoe after it has been side lasted by the machine, showing the upper fastened to the sole by tacks along the shank portion and by cement at the forepart.

The invention is illustrated as embodied in a machine of the type disclosed in the above-mentioned Letters Patent and accordingly only such features of the general organization as it is necessary to refer to for an understanding of the invention will be described herein in detail.

It will be understood that the shoe on its last is supported in the hands of the operator and is presented successively in different positions in the progressive lasting of its opposite sides. To assist in determining the proper relation of the shoe to the lasting instrumentalities the machine is provided with an edge gage 20 arranged to engage the side of the shoe at or near the edge of the insole and with a shoe bottom rest 22 arranged to engage the outer face of the insole. The machine is provided with a gripper comprising a pair of cooperating jaws 24 to which the usual closing, updraw and overdraw movements are imparted by mechanism which is substantially the same as that shown in the above-mentioned Letters Patent. For wiping the marginal portion of the upper inwardly over the insole, there is provided a wiper 26 mounted on a slide 28 which is movable along a horizontal guideway in the head 30 of the machine and is operated by a cam 32 (Fig. 1) on a cam shaft 34 journaled in suitable bearings in the head 30. The shape of the cam 32 is such that one complete reciprocation is imparted to the slide 28 in each cycle of operations of the machine to cause the wiper 26 to wipe the marginal portion of the upper inwardly over the outer face of the insole and to withdraw. It will be understood that when the wiper is in its rearward position a tack is fed from one or the other of a pair of raceways 36, 38 (Fig. 5) into a tack pocket 40, formed in the wiper, from which it is driven by a driver 42 after the completion of the forward movement of the wiper.

The tack driver 42 is fastened to a driver bar 44 which is movable in a guideway formed in a carrier 46 journaled for swinging movement on trunnions 48, the journals being formed in a bracket 50 fast to the head 30. The slide 28 carries an adjustable screw 52 (Fig. 2) the head of which is arranged to engage an abutment 54 on the carrier 46 near the end of the forward movement of the slide 28 and to swing the carrier 46 with it, thus alining the driver 42 with the tack pocket 40 in the wiper 26 and maintaining such alinement during the remainder of the overwiping operation. The driver bar 44 is raised by a cam 56 on the shaft 34 against the resistance

of a torsion spring which acts through an arm 60 and a strut 62 to impart tack driving movement to the driver 42 when the driver bar is released by the cam to the action of this spring after the completion of the forward movement of the wiper 26 and the slide 28.

It will be understood that the raceways 36 and 38 are adapted to receive tacks of different lengths and that the machine provides for automatic shifting of the raceways to bring one or the other of them into operative relation to mechanism for separating a tack from either of the raceways and delivering it to the wiper 26. The tack separating mechanism is not herein described in detail since it is substantially the same as that shown in Letters Patent of the United States No. 1,623,279, granted on April 5, 1927, upon an application of T. H. Seely. The raceways 36 and 38 at their upper end are pivoted in the front wall of a tack pot 64 and at their lower end are connected by an adjustable link 66 to a block 68 which is adjustably secured to an irregularly shaped rocking lever 70 by a cap screw 72. Mounted in the block 68 is a spring-pressed plunger 74 (Fig. 11) having a conical end which engages a similarly shaped recess in the end of the link 66 to form a pivot for the link and an operative connection between the link and the lever 70. The lever 70 is fulcrumed on a vertical shaft 76 (Fig. 3) mounted to turn in bearings 78, 80 on the head 30, the lever 70, as shown in Fig. 12 being formed to embrace the bearing 78. Movement of the lever 70 to shift the raceways 36, 38 and to control the kind of tacks delivered to the wiper 26 is effected by power of the machine under the control of the operator by mechanism which is substantially the same as that shown in the above-mentioned Letters Patent No. 1,623,279 and accordingly, need not be described herein in detail. It will be understood that either raceway 36, 38 may be moved into operative relation to the tack separating mechanism and the wiper 26 and that when in that relation the end of the raceway is in alinement with a tack slot 81 in a throat plate 83. The tack slot 81 terminates in an eye 85 through which the tack drops into the tack pocket 40 in the wiper. Between the throat plate 83 and the end of the raceways is a separator 87 which is reciprocated once in each cycle to separate the endmost tack from that raceway which is in tack supplying position. After the tack has been separated it is moved by the separator along the slot 81 and into position to drop through the eye 85 into the tack pocket 40. The machine as thus far described is constructed substantially as heretofore.

For purposes of this invention there is provided mechanism which may be rendered operative at will for imparting to the wiper 26 at the end of each overwiping movement a hammer blow to cause the wiper to force the overwiped margin of the upper into firm adherence to the outer face of the insole in lasting the shoe with cement instead of with tacks. The wiper 26 is pivotally connected to a bracket 82 which is secured to the slide 28 by screws 84 (Figs. 6 and 7). In the construction shown the rear end portion of the wiper is forked to straddle a depending lug 86 on the bracket 82 (Fig. 13) and mounted in one of the arms of the forked end of the wiper is a spring-pressed plunger 88 which is arranged to engage a lateral projection 90 on the bracket 82 and to hold the wiper in engagement with a shoulder 92 on the bracket. The wiper 26 has

fast thereon a plate 93 provided with a rearwardly extending arm 94 arranged to engage a substantially L-shaped member or plate 96 adjustably secured to a lever 98 pivoted at 100 (Figs. 4, 5, and 10) to a bracket 102 having a tongue-and-groove connection with the head 30 and fastened to the head by a screw 104. When the plate 96 is in the position shown in Figs. 1, 4, and 6 it acts by engagement with the arm 94 to hold the wiper against swinging movement relatively to the bracket 82 with the wiper in engagement with the shoulder 92 on the bracket. For imparting a hammer blow to the wiper there is provided a hammer 106 (Figs. 6, 7 and 9) which is arranged to engage the head 108 of an upwardly extending arm 110 of the plate 93. The hammer 106 is pivoted on a stud 112 (Fig. 9) secured to the slide 28 and is operated by a torsion spring 114 one end of which is connected to a member 116 which may be turned to adjust the tension of the spring and is held in adjusted position with teeth 118 on the member 116 in engagement with recesses formed in the end of the stud 112 by a screw 120 threaded into the stud. The hammer 106 is provided with a rearwardly extending arm 122 arranged to engage an adjustable stop, illustrated as a fiber washer 124, to limit operative movement of the hammer, the fiber washer being carried by an adjustable screw 126 (Figs. 6 and 7) threaded through a boss 128 on a plate 130 secured to the head 30. A lever or latch 132 pivotally mounted on the slide 28 and held in engagement with an abutment 134 on the hammer by a spring 136 acts normally to hold the hammer 106 in an elevated position with its operating spring 114 under tension.

The machine is provided with mechanism for operating the latch 132 to release the hammer 106 to the action of its operating spring 114 at the proper time in the cycle of the machine and for moving the plate 96 into a position in which the arm 94 of the wiper is moved out of engagement with the plate near the end of the forward movement of the slide 28, thereby releasing the wiper for swinging movement in response to the action of the hammer 106 thereon. Fast to a shaft 140 mounted to turn in bearings 142, 144 on the head of the machine is a hand lever 146 (Figs. 1, 3, and 4). Secured to the upper end of the shaft 140 is an arm 148 connected by a link 150 to an arm 152 formed on a sleeve 154 rotatably mounted on the shaft 76. Formed on the sleeve 154 is a second arm 156 connected by a link 158 to an arm 160 clamped to the upper end of a shaft 162 mounted to turn in a bearing 164 formed on the head 30 (Figs. 2 and 3). Secured to the lower end of the shaft 162 is an arm 166 connected by a short link 168 to an arm 170 on the lever 98. When the parts are in the positions shown in Fig. 4 with the member 96 in position to lock the wiper 26 against swinging movement relatively to the bracket 82, the arm 166 and the link 168 are in a substantially straight condition with a stop 172 on the hand lever 146 in engagement with an abutment 174 on the head 30. Movement of the hand lever 146 from the position shown in Fig. 4 to the position shown in Fig. 5 swings the member 96 through the connections above described into a position in which the rearwardly extending arm 94 of the wiper is moved out of engagement with this member in the forward movement of the slide 28, the construction being such that the wiper 26 is thus released for swinging movement relatively

to the slide near the end of the overwiping movement of the wiper. Fast to one end of a rockshaft 175 mounted in the head of the machine is a rearwardly extending arm 176 (Figs. 1, 6, and 7) having its end portion formed as an abutment 178 and fast to the opposite end of the rockshaft 175 is an upwardly extending arm 180 carrying an adjustable screw 182. A spring 184 extending between an arm 185 fast to the shaft 175 and the head 30 tends to swing the shaft 175 and the arm 180 in a direction to hold the screw 182 in engagement with the edge face 186 of a cam plate 188 which is secured to the hand lever 146 by a screw 190. The shape of the edge face 186 (Figs. 4 and 5) is such that as the hand lever is swung in the direction to move the member 96 into the position shown in Fig. 5 the shaft 175 is rotated through the swinging of the arm 180 in a direction to move the abutment 178 from the position shown in Fig. 6 to the position shown in Fig. 7. With the abutment 178 in the position shown in Fig. 7, as the slide 28 is moved forwardly an upwardly extending arm 192 on the latch 132 is moved into engagement with the abutment so that in the continued forward movement of the slide 28 the latch 132 is swung against the resistance of the spring 136 out of engagement with the abutment 134 on the hammer 106, thereby releasing the hammer to the action of its operating spring 114, the arrangement of the parts being such that the hammer is thus released substantially at the end of the forward movement of the slide 28. With the return of the parts to starting positions the hammer 106 is swung reversely in the direction to tension its operating spring by the engagement of a roll 194 on the arm 122 with an inclined face 196 on the plate 130, the inclination of the face 196 being such that the hammer is swung far enough in the return movement of the slide 28 to permit the latch 132 again to engage the abutment 134 on the hammer 106.

Forward swinging movement of the hand lever 146 is limited by the engagement of a stop 200 on the hand lever with a fixed abutment 202 on the head 30. When the hand lever is swung forwardly from the position shown in Fig. 4, the arm 160 fast to the shaft 162 is swung in a clockwise direction. Secured to the shaft 162 is an arm 204 provided with a cam slot 206 concentric with the axis of the shaft 162 (Figs. 4 and 5). Formed on a bracket 208 (Figs. 2 and 3) on which the raceway supporting block 210 is mounted is a bearing 212 for a rockshaft 214 having secured to its upper end an arm 216 provided with a lug 218 extending into a central recess 220 formed in the raceway supporting block 210 (Figs. 4 and 5). Fast to the lower end of the rockshaft 214 is an arm 222 carrying a roll 224 which is arranged to enter the cam slot 206 in the arm 204 as this arm is swung in a clockwise direction with the arm 160. As the arm 204 engages the cam roll 224 in the cam slot 206 the arm 222, through the rockshaft 214 and the arm 216, is swung in a direction to cause the raceways 36, 38, through 55 the engagement of the lug 218 with the raceway supporting block 210 in the recess 220 in the block, to be swung into a neutral position (Fig. 5) in which position neither raceway is in alignment with the tack slot 81 in the throat plate 83 so 60 that no tack will be delivered from either of the raceways through the tack-separating mechanism to the wiper 26. When the hand lever 146, therefore, is swung forwardly to the position shown in Fig. 5, the feeding of the tacks is inter- 75

rupted by the movement of the raceways into a neutral position. For holding the hand lever 146 in its rearward position with the stop 172 in engagement with the abutment 174 or in its forward position with the stop 200 in engagement with the abutment 202 there is provided a spring 203 (Fig. 1) connected at one end to a pin 205 projecting from the head 30 and at the other end to a pin 207 carried by an arm 209 on the 10 sleeve 154.

The illustrated machine is further provided with means for stopping the operation of the driver 42 in response to the forward swinging movement of the hand lever 146. Formed on the 15 driver bar 44 (Fig. 3) is an abutment 226 and pivotally mounted on the bracket 50 is a latch 228 for engaging the abutment to prevent operative movement of the driver bar 44. Fast to a slide 232 movable in a guideway in the bracket 20 50 is a stop 230 arranged by engagement with a laterally extending arm 234 on the latch 228 to hold the latch normally out of engagement with the abutment 226. The arm 234 of the latch is held in engagement with the stop 230 by a 25 spring 236 extending between the arm and the bracket 50. Projecting downwardly through an enlarged opening in an arm 238 on the stop 239 is a pin 240 which is threaded into an arm 242 on the sleeve 154 and is provided with a nut 244 30 for locking it against endwise movement in the arm 242. As the hand lever 146 is swung forwardly from the position shown in Fig. 4 the sleeve 154 is rotated in a clockwise direction to move the stop 230 to the left (Fig. 3) out of engagement with arm 234. Movement of the stop 230 out of engagement with the arm 234 permits the spring 236 to swing the latch 228 into a position beneath the abutment 226 to prevent operative movement of the driver 42. It will be 35 understood that as the hand lever 146 is swung rearwardly from the position shown in Fig. 5, the stop 230 is moved to the right (Fig. 3) in response to counterclockwise movement of the sleeve 154. As the stop 230 is moved to the right 40 it engages an inclined face 246 on the arm 234 and swings the arm in a direction to move the latch from beneath the abutment 226 to permit the operation of the driver.

It will be understood that the position of the 50 shoe laterally is determined by the edge gage 20 which is arranged to engage the shoe substantially opposite the edge of the insole. In lasting a shoe with cement the position of the shoe laterally should preferably be such as to cause the 55 wiper to act on the marginal portion of the upper over substantially its entire width to wipe it inwardly over the insole and to press it into position to adhere thereto. Since the tacks are usually inserted substantially midway between 60 the edge of the shoe bottom and the edge face of the overlaid margin of the upper in lasting with tacks, the illustrated machine is provided with means under the control of the operator for adjusting the edge gage rearwardly to extend the 65 wiping effect of the wiper when lasting with cement. For this purpose the edge gage 20 is adjustably secured to a member 248 slidably mounted on the bracket 102 (Figs. 1, 2, 10, 15, and 16). The member 248 carries an adjustable screw 250 70 which when the parts are in the positions shown in Fig. 10, is held by a spring 254 extending between the member 248 and the bracket 102 in engagement with a curved face 252 on the lever 98. A plate 256 having a tongue-and-groove connection with the slide 248 is adjustably secured 75

thereto by a screw 258 threaded into the slide and extending through a slot in the plate. Fast to the plate 256 is a stop, illustrated as a pin 260, having its upper end portion cut away to provide a flat surface for engaging the end face 262 of the bracket 102. Fig. 10 shows the parts in the positions that they occupy when the machine is used for lasting a shoe with tacks. When it is desired to last a shoe with cement the lever 98 in response to the forward swinging movement of the hand lever 146 is swung from the position shown in Fig. 4 to the position shown in Fig. 5. As the lever 98 is thus swung the slide 248 and the edge gage 20 are moved rearwardly by the spring 254 until the stop 260 engages the end face 262 of the bracket 102. It will be seen that by adjusting the plate 256 relatively to the slide 248 the rearward position of the edge gage 20 may be varied to vary the position of the shoe laterally and thereby to vary the extent of inward movement of the wiper over the bottom of the shoe as may be necessary to take care of variations in the width of the lasting margins of the uppers of different shoes. It will be evident that with the parts in the positions shown in Fig. 5 rearward movement of the gage 20 is prevented by engagement of the stop 260 with the end face 262 of the bracket 102. When the hand lever 146 is swung rearwardly the lever 98 is swung into the position shown in Fig. 4. As the lever 98 is thus swung the slide 248 and the gage 20 are moved against the resistance of the spring 254 forwardly by the engagement of the curved face 252 of the lever 98 with the screw 250, the construction being such that the lever 98 is held against reverse swinging movement to prevent rearward displacement of the gage 20 by the positions of the arms 166, 170 and the short link 168. It will be evident that the position of the shoe laterally may be varied to vary the distance 40 from the edge of the shoe bottom at which the tacks are inserted by adjusting the screw 250.

It will be understood that when the hand lever 146 is in the position shown in Fig. 4 the machine is set to wipe the marginal portion of the upper in each lasting location over the outer face of the sole and to drive a tack from the wiper at the end of the overwiping operation to fasten the upper to the sole. When it is desired to last a shoe, or a portion thereof as, for example, the forepart, without tacks, the hand-lever 146 is swung forwardly to the position shown in Fig. 5. Forward swinging movement of the hand lever moves the abutment 178 into latch-tripping position, causes the raceways 36, 38 to be moved 55 into a neutral position, the arm 98 to be swung in a direction to move the locking plate 96 into a position to release the wiper 26 for swinging movement substantially at the end of its inward movement and to permit the spring 254 to move 60 the edge gage 20 rearwardly, and also moves the stop 230 into a position in which the latch 228 is released to the action of the spring 236 for engagement with the abutment 226 to prevent operative movement of the driver 42. With the 65 hand lever in the position shown in Fig. 5, the machine is set to wipe the marginal portion of the upper over the sole and to operate the wiper substantially at the end of its overwiping movement by a hammer blow to cause it to force the 70 overwiped margin firmly into adhering relation to the outer face of the sole, to the marginal portion of which, and to the marginal portions also of the upper, cement has previously been applied.

Fig. 18 shows a shoe after it has been side lasted by the machine, the upper being fastened to the shank portion of the sole by tacks and along the sides of the forepart by cement. It will be understood, however, that the machine is not limited to this particular use, nor is the invention limited to an organization which drives fastenings of that particular character.

Having described the invention, what I claim as new and desire to secure by Letters Patent of the United States is:

1. In a lasting machine, the combination with means for shaping an upper over a last, and a wiper for wiping the marginal portion of the upper inwardly over a sole on the last, of different devices arranged for alternative use respectively to drive fastenings to fasten the upper to the sole after the upper has been wiped inwardly by the wiper or to operate said wiper by a hammer blow to force the overwiped marginal portion of the upper into adhering relation to the sole in lasting the shoe with cement instead of with driven fastenings.

2. In a lasting machine, the combination with means for shaping an upper over a last, of a wiper for wiping the marginal portion of the upper inwardly over a sole on the last, different devices arranged for use respectively to drive fastenings to fasten the upper to the sole after the upper has been wiped inwardly by the wiper or to operate said wiper by a hammer blow to force the overwiped marginal portion of the upper against the outer face of the sole, automatic means for operating both said devices, and means for stopping the operation of one of said devices when the other device is in use.

3. In a lasting machine, the combination with means for shaping an upper over a last, a wiper for wiping the marginal portion of the upper inwardly over a sole on the last, and means for fastening the upper with tacks to the sole after the upper has been wiped inwardly by the wiper, of means for imparting to the wiper a downward tipping movement substantially at the end of its inward movement to increase the pressure of the wiper on the upper in lasting the shoe with cement instead of with tacks, and means for rendering the tack-fastening means inoperative when said last-named means is in use.

4. In a lasting machine, the combination with means for shaping an upper over a last, a wiper for wiping the marginal portion of the upper inwardly over a sole on the last, and means for fastening the upper with tacks to the sole after the upper has been wiped inwardly by the wiper, of a device arranged for use at the will of the operator to impart to said wiper after the movement of the wiper inwardly over the sole has been substantially completed a hammer blow to cause the wiper to press the overwiped margin of the upper into adhering relation to the outer face of the sole in lasting the shoe with cement instead of with tacks, and means for rendering the tack-fastening means inoperative when said device is in use.

5. In a lasting machine, the combination with means for shaping an upper over a last, a wiper for wiping the marginal portion of the upper inwardly over a sole on the last, and a driver for driving a fastening from said wiper to fasten the upper to the sole, of a hammer arranged for use at the will of the operator to deliver a blow to said wiper to cause the wiper to force the overwiped margin of the upper against the sole in lasting the shoe with cement instead of with

driven fastenings, and means for stopping the operation of the driver when the hammer is in use.

6. In a lasting machine, the combination with means for shaping an upper over a last, a wiper movable inwardly over the bottom of the last to wipe the marginal portion of the upper over the outer face of a sole on the last, and a driver for driving a fastening from said wiper to fasten the upper to the sole, of a hammer for delivering a blow to said wiper to cause it to force the upper by impact against the outer face of the sole in lasting the shoe with cement instead of with driven fastenings, and means for rendering the hammer operative and the driver inoperative at will.

7. In a lasting machine, the combination with means for shaping an upper over a last, a wiper for wiping the marginal portion of the upper inwardly over a sole on the last, and a driver for driving a fastening from said wiper to fasten the upper to the sole, of a hammer for delivering a blow to said wiper to cause it to force the overwiped marginal portion of the upper into adhering relation to the sole in lasting the shoe with cement instead of with driven fastenings, mechanism under the control of the operator for rendering the hammer operative, and means for preventing operative movement of the driver when the hammer is used.

8. In a lasting machine, the combination with a gripper for pulling an upper over a last, a wiper for wiping the marginal portion of the upper inwardly over a sole on the last, and a driver for driving fastenings from said wiper to fasten the upper to the sole, of a spring-operated hammer for delivering a blow to said wiper to cause it to force the marginal portion of the upper into adhering relation to the sole in lasting the shoe with cement instead of with driven fastenings, a latch for holding the hammer in a retracted position with its operating spring under tension, a member movable relatively to the latch into position to operate the latch to release the hammer to the action of its operating spring substantially at the end of the inward movement of the wiper, and means for preventing operative movement of the driver when said member has been moved into that relation to the latch.

9. In a lasting machine, the combination with means for shaping an upper over a last, a wiper for wiping the marginal portion of the upper inwardly over a sole on the last, and a driver for driving fastenings to fasten the upper to the sole, of a hammer for delivering a blow to said wiper to increase its pressure on the upper in lasting the shoe with cement instead of with driven fastenings, a spring for operating said hammer, a latch for holding the hammer in an inoperative position with the spring under tension, an abutment movable into and out of position to trip said latch to release the hammer to the action of its operating spring substantially at the end of the inward movement of said wiper, a controlling lever for moving the abutment into latch-tripping position, and mechanism operative in response to such movement of the lever for stopping the operation of the driver.

10. In a lasting machine, the combination with means for shaping an upper over a last, a wiper for wiping the marginal portion of the upper inwardly over a sole on the last, and a driver for driving fastenings to fasten the upper to the sole, of mechanism for operating the wiper by a hammer blow to cause it to force the overwiped

margin of the upper firmly into adhering relation to the outer face of the sole in lasting the shoe with cement instead of driven fastenings, said mechanism comprising a spring-operated hammer for delivering a blow to said wiper, a latch for preventing operative movement of the hammer with said spring under tension, an abutment movable into and out of position to operate said latch to release the hammer to the action of its operating spring substantially at the end of the inward movement of the wiper, a member movable by the operator to control said abutment, and means for stopping the operation of the driver when the abutment is in operative position.

11. In a lasting machine, the combination with means for shaping an upper over a last, a wiper for wiping the marginal portion of the upper inwardly over a sole on the last, a driver for driving fastenings to fasten the upper to the sole, and means for operating the driver comprising a driver bar, of a spring-operated latch arranged by engagement with an abutment on said driver bar to prevent operative movement of the driver, a stop for holding said latch against the resistance of its operating spring out of engagement with said abutment and movable to release the latch to the action of its operating spring for engagement with said abutment, a spring-operated hammer for striking said wiper substantially at the end of its inward movement to increase the pressure of the wiper on the upper in lasting the shoe without driven fastenings, a lever for preventing operative movement of the hammer with said spring under tension, an arm movable into and out of position to operate said lever to release the hammer to the action of its operating spring, a controlling member for said arm, and connections between said controlling member and the stop for moving the stop in a direction to release said spring-operated latch for engagement with said abutment by the movement of said member.

12. In a machine for lasting shoes in which the marginal portion of the upper is secured in lasted relation to a sole on the last by an adhesive, the combination with means for shaping an upper over a last, of a wiper for wiping the marginal portion of the upper inwardly over a sole on the last, a slide movable forwardly to impart to the wiper its overwiping movement, a spring-operated hammer on said slide for striking said wiper to increase its pressure on the upper, a latch for holding the hammer in a retracted position with its operating spring under tension during the forward movement of the slide, and means mounted independently of the slide for operating the latch to release the hammer to the action of its operating spring substantially at the end of the forward movement of the slide.

13. In a machine for lasting shoes in which the marginal portion of the upper is secured in lasted relation to a sole on the last by an adhesive, the combination with means for shaping an upper over a last, of a wiper for wiping the marginal portion of the upper inwardly over a sole on the last, a slide movable forwardly to impart to said wiper its overwiping movement and movable thereafter rearwardly to retract said wiper, a spring-operated hammer on said slide for striking the wiper to increase its pressure on the upper, a latch for holding the hammer against movement relatively to the wiper, means for retracting the hammer into latching position in response to the rearward movement of said

slide, and a member mounted independently of the slide for tripping said latch to release the hammer to the action of its operating spring after the overwiping movement of the wiper has been substantially completed.

14. In a machine for lasting shoes in which the marginal portion of the upper is secured in lasted relation to a sole by an adhesive, the combination with means for shaping an upper over a last, of a wiper for wiping the marginal portion of the upper inwardly over a sole on the last, a slide movable forwardly to impart to said wiper its movement inwardly over the sole and movable thereafter rearwardly to retract said wiper, a spring-operated hammer pivotally mounted on said slide for striking the wiper to increase its pressure on the upper, said hammer having a rearwardly extending arm, a roll mounted on said arm, a cam arranged by engagement with said roll to swing said hammer in a direction to tension its operating spring in response to the rearward movement of the slide, a latch for holding the hammer against swinging movement with said spring under tension, and a member for tripping the latch to release the hammer to the action of its operating spring substantially at the end of the forward movement of the slide.

15. In a machine for lasting shoes in which the marginal portion of the upper is secured in lasted relation to a sole by an adhesive, the combination with means for shaping an upper over a last, of a wiper for wiping the marginal portion of the upper inwardly over a sole on the last, a slide movable forwardly to impart to said wiper its overwiping movement and movable thereafter rearwardly to retract said wiper, a hammer on said slide for imparting a blow to said wiper substantially at the end of its overwiping movement to cause the wiper to press the upper into adhering relation to the sole, operating means for said hammer comprising a spring arranged to be tensioned in response to the rearward movement of the slide, and means for holding the hammer in a retracted position with said spring under tension and for releasing the hammer to the action of its operating spring after the forward movement of the slide has been substantially completed.

16. In a machine for lasting shoes in which the marginal portion of the upper is secured in lasted relation to a sole by an adhesive, a wiper for wiping the marginal portion of an upper inwardly over the outer face of a sole on a last, a slide for moving said wiper inwardly over the bottom of the shoe, said wiper being mounted on said slide for swinging movement heightwise of the shoe, a hammer on said slide for striking said wiper substantially at the end of its inward movement to increase the pressure of said wiper on the upper, and means for holding said wiper against swinging movement heightwise of the shoe and for releasing it for such swinging movement prior to the operation of said hammer.

17. In a machine for lasting shoes in which the marginal portion of the upper is secured in lasted relation to a sole by an adhesive, a wiper for wiping the marginal portion of an upper inwardly over the outer face of a sole on a last, a slide for moving said wiper inwardly over the bottom of the shoe, said wiper being mounted on said slide for swinging movement heightwise of the shoe, a hammer on said slide for striking said wiper to increase its pressure on the upper, a spring for operating said hammer, a latch for holding said hammer in an inoperative position

with said spring under tension, means for locking said wiper against swinging movement heightwise of the shoe and for releasing it for such swinging movement after it has substantially completed its inward movement over the shoe bottom, and means for thereafter operating said latch to release the hammer to the action of its operating spring.

18. In a lasting machine, the combination with means for shaping an upper over a last, of a wiper for wiping the marginal portion of the upper inwardly over a sole on the last and for pressing it into position to adhere to the sole through the action of cement, a slide movable forwardly to impart to said wiper its inward movement and movable thereafter rearwardly to retract the wiper, a spring-operated hammer for striking said wiper to increase the pressure of the wiper on the upper, means for retracting said hammer and for tensioning its operating spring in response to the rearward movement of said slide, a latch for holding the hammer in a retracted position with said spring under tension, and a member into engagement with which said latch is carried in the forward movement of the slide for operating the latch to release said hammer to the action of its operating spring after the inward movement of the wiper has been substantially completed.

19. In a lasting machine, the combination with means for shaping an upper over a last, means for fastening the upper to a sole on the last comprising a wiper movable inwardly over the bottom of the shoe to wipe the marginal portion of the upper over the sole, and means for feeding fastenings to said wiper, of a device for operating said wiper by a hammer blow to press the overwiped margin of the upper into adhering relation to the sole in lasting the shoe with cement instead of with fastenings, and connected mechanisms for rendering said device operative and the fastening-feeding means inoperative at will.

20. In a lasting machine, the combination with means for shaping an upper over a last, means for fastening the upper with tacks to a sole on the last comprising a driver, a wiper movable inwardly over the bottom of the shoe to wipe the marginal portion of the upper over the sole and to position a tack for the operation of said driver, and means for feeding tacks to said wiper, of a spring-operated hammer arranged to be rendered operative or inoperative at will to deliver a blow to said wiper substantially at the end of the inward movement of the wiper to cause it to press the over-wiped margin of the upper into adhering relation to the outer face of the sole in lasting the shoe with cement instead of with tacks, and means for stopping the operation of the driver and for interrupting the feeding of the tacks when said hammer is in operation.

21. A lasting machine having, in combination, means for shaping an upper over a last, a wiper movable inwardly over the bottom of the last to wipe the marginal portion of the upper over a sole on the last, a fastening-inserting driver, driver-operating means, fastening-feeding means, a hammer for striking said wiper to increase its pressure on the upper, a spring for operating said hammer, a latch for holding the hammer with said spring under tension, a member movable into position to operate said latch to release the hammer substantially at the end of the inward movement of said wiper, a hand lever swingable to move said last-named member into such relation to the latch, and mechanism controlled by the

swinging of said hand lever for rendering the driver-operating means and the fastening-feeding means inoperative.

22. In a lasting machine, the combination with means for shaping an upper over a last, means for fastening the upper with tacks to a sole on the last comprising a member for receiving tacks, a raceway for supplying tacks to said member, and means for moving said member inwardly over the bottom of the shoe into upper-fastening position, of means for moving the raceway out of operative relation to said tack-receiving member to interrupt the supply of tacks, and means arranged to be rendered operative when the raceway has been moved out of operative relation to said tack-receiving member for delivering a hammer blow to said member substantially at the end of its inward movement to cause said member to press the marginal portion of the upper into firm adhering relation to the outer face of the sole in lasting the shoe with cement instead of with tacks.

23. In a lasting machine, the combination with means for shaping an upper over a last, means for fastening the upper with tacks to a sole on the last comprising a wiper having a tack-receiving pocket formed therein, means for moving said wiper inwardly over the bottom of the shoe into upper-fastening position, a pair of raceways for supplying tacks of different kinds to said wiper, and power means for shifting the raceways to present either raceway in operative relation to said wiper, of operator-controlled means for shifting the raceways into a neutral position to interrupt the supply of tacks, and means arranged to be rendered operative when said raceways have been moved into a neutral position for delivering a blow to said wiper substantially at the end of its inward movement to increase the pressure of the wiper on the upper in lasting the shoe with out tacks.

24. In a lasting machine, the combination with means for shaping an upper over a last, and means for fastening the upper with tacks to a sole on the last comprising a wiper for wiping the marginal portion of the upper inwardly over the sole, said wiper having a tack-receiving pocket, and a raceway for supplying tacks to said wiper, of a spring-operated hammer for delivering a blow to said wiper substantially at the end of its inward movement to cause the wiper to force the upper into adhering relation to the sole in lasting the shoe with cement instead of with tacks, a latch for holding the hammer in a retracted position with its operating spring under tension, a pivoted arm movable into and out of position to operate said latch to release the hammer to the action of its operating spring, a cam plate mounted for turning movement to move said arm into position to operate the latch, and connections between said cam plate and the raceway for moving the raceway out of operative relation to the wiper to interrupt the supply of tacks.

25. In a lasting machine, the combination with means for shaping an upper over a last, means for fastening the upper with tacks to a sole on the last comprising a wiper having a tack-receiving pocket formed therein, a raceway for supplying tacks, a separator for separating a tack from said raceway and delivering it into the tack pocket in said wiper, and a slide for moving said wiper inwardly over the bottom of the shoe into upper-fastening position, of a spring-operated hammer for delivering a blow to said wiper substantially at the end of its inward movement to cause the

wiper to force the upper firmly into adhering relation to the sole in lasting the shoe with cement instead of with tacks, a latch for holding said hammer in a retracted position with its operating spring under tension, an arm movable into and out of position to trip said latch, a controlling member for moving said arm into position to trip the latch, and connections between said controlling member and the raceway for moving 10 the raceway out of operative relation to said separator to stop the feeding of the tacks by the movement of said member.

26. In a lasting machine, the combination with means for shaping an upper over a last, and means 15 for fastening the upper with tacks to a sole on the last comprising a driver, a wiper having a tack pocket formed therein, a raceway for supplying tacks, a separator for separating a tack from said raceway and delivering it to said wiper, 20 and a slide for moving the wiper inwardly over the bottom of the shoe to wipe the marginal portion of the upper over the sole and to position a tack for the operation of said driver, of a spring-operated hammer on said slide for striking 25 the wiper substantially at the end of its inward movement to increase the pressure of the wiper on the upper in lasting the shoe without tacks, a latch for holding the hammer in an elevated position with its operating spring under tension, 30 an arm mounted independently of said slide and movable into and out of position to operate said latch to release the hammer to the action of its operating spring, a hand lever for moving the arm into operative relation to the latch, and 35 mechanism for stopping the operation of the driver and for moving the raceway out of operative relation to said separator to stop the feeding of the tacks by the movement of said hand lever.

27. In a lasting machine, the combination with 40 means for shaping an upper over a last, and means for fastening the upper with tacks to a sole on the last comprising a driver, a wiper, means for feeding tacks to said wiper, and a slide for moving the wiper inwardly over the bottom of the 45 shoe to wipe the marginal portion of the upper over the outer face of the sole and to position a tack for the operation of said driver, said wiper being mounted on the slide for swinging movement heightwise of the shoe, of a locking member for holding the wiper against said swinging 50 movement, a device arranged for use at the will of the operator for delivering a blow to said wiper substantially at the end of its inward movement to increase the pressure of the wiper on the upper, 55 a lever movable by the operator to control said device, connections between said lever and the locking member for moving the locking member into a position to permit swinging movement of the wiper in response to the action of said device thereon, and mechanism controlled by said lever for preventing the tacking operation when said device is in use.

28. In a lasting machine, the combination with 60 means for shaping an upper over a last, a wiper movable inwardly over the bottom of the shoe to wipe the marginal portion of the upper over a sole on the last, a slide for imparting to said wiper its inward movement, said wiper being mounted on the slide for swinging movement 65 heightwise of the shoe, and a driver for driving fastenings from said wiper to fasten the upper to the sole, of a hammer for striking said wiper after its inward movement has been substantially completed to cause the wiper to force the upper into firm adhering relation to the sole in lasting the shoe with cement instead of with driven 70 fastenings, means for rendering the hammer operative and the driver inoperative at will, and means controlled by said last-named means for effecting an adjustment of the edge gage widthwise of the shoe.

75 a latch for holding said hammer in a retracted

position with its operating spring under tension, a locking plate for preventing swinging movement of said wiper relatively to the slide, a member movable into position to operate said latch to release the hammer to the action of its operating spring substantially at the end of the inward movement of the wiper, an arm for moving the locking plate into a position to release the wiper for swinging movement, a controlling-lever for moving said member and arm, and mechanism also controlled by said lever for preventing operative movement of the driver.

29. In a lasting machine, the combination with means for pulling an upper over a last successively in different locations along the side of the last as 15 the shoe is presented in different positions, a shoe bottom rest and an edge gage for controlling the shoe, and a wiper movable inwardly over the bottom of the shoe in each location to wipe the marginal portion of the upper over a sole on the last, of different devices arranged for alternative use respectively to drive fastenings from said wiper to fasten the upper to the sole or to operate said wiper by a hammer blow to force the overwiped margin of the upper firmly into adhering 25 relation to the sole in lasting the shoe with cement instead of with driven fastenings, and mechanism constructed to enable the operator to effect a quick adjustment of the edge gage widthwise of the shoe to position the shoe differently in lasting with cement or with driven 30 fastenings.

30. In a lasting machine, the combination with means for pulling an upper over a last successively in different locations along the side of the last as the shoe is presented in different positions, a shoe bottom rest and an edge gage for controlling the shoe, and a wiper movable inwardly over the bottom of the shoe in each location to wipe the marginal portion of the upper over a sole on the last, of different devices arranged for use respectively to drive fastenings from said wiper to fasten the upper to the sole or to operate said wiper by a hammer blow to press the upper into adhering relation to the sole in lasting the shoe with cement instead of with driven fastenings, manually-controlled means for rendering one of said devices inoperative when the other device is in use, and means controlled by said last-named means for moving 50 the edge gage into a different position widthwise of the shoe to change the position of the shoe laterally in lasting the shoe with cement instead of with driven fastenings.

31. In a lasting machine, the combination with means for pulling an upper over a last successively in different locations along the side of the last as the shoe is presented in different positions, a shoe bottom rest and an edge gage for controlling the shoe, a wiper movable inwardly over the bottom of the shoe in each location to wipe the marginal portion of the upper over a sole on the last, and a driver for driving fastenings from said wiper to fasten the upper to the sole, of a hammer for striking said wiper after its inward movement has been substantially completed to cause the wiper to force the upper into firm adhering relation to the sole in lasting the shoe with cement instead of with driven fastenings, means for rendering the hammer operative and the driver inoperative at will, and means controlled by said last-named means for effecting an adjustment of the edge gage widthwise of the shoe.

32. In a lasting machine, the combination with

means for pulling an upper over a last successively in different locations along the side of the last as the shoe is presented in different positions, a shoe bottom rest and an edge gage for controlling the shoe, a wiper movable inwardly over the bottom of the shoe in each location to wipe the marginal portion of the upper over a sole on the last, and a driver for driving fastenings from said wiper to fasten the upper to the sole, of a spring-operated hammer for delivering a blow to said wiper substantially at the end of its inward movement to cause the wiper to press the upper into adhering relation to the

sole in lasting the shoe with cement instead of with driven fastenings, a latch for holding said hammer in a retracted position with its operating spring under tension, a device movable into position to operate said latch to release the hammer to the action of its operating spring in response to the inward movement of the wiper, a member for moving said device, and mechanism controlled by said member for stopping the operation of the driver and imparting to the edge gage a movement widthwise of the shoe. 5 10

BENJAMIN B. BLANCHARD.
